INTERNAL COMBUSTION ENGINE

George Grover, Jr., Hadley, Mich.

Application September 17, 1937, Serial No. 164,385

2 Claims. (Cl. 123—56)

This invention relates to internal combustion engines. It has particularly to do with a double block engine, each block having a number of oppositely disposed pistons acting upon a master piston which, in turn, is connected to the drive shaft.

An object of the invention is to provide two master pistons, oppositely disposed, each having a plurality of piston elements secured thereto so that the pistons in each block move in unison with their respective master pistons.

Another object of this invention is to provide a highly powered engine adapted to produce greater horsepower per pound than any previous designed engine, and which, due to its novel design, is extremely well balanced and permits the use of skirtless power pistons.

A further object is to provide an internal combustion engine with a large number of power cylinders, still maintaining a simple connection to the power shaft. In the example shown it is necessary to use only two rods with bearings for 32 power cylinders. A further feature of this novel design is that the torque on the crank shaft is evenly balanced at all times. The engine is especially adapted to motor vehicles having a rear mounting for the engine since the engine can be mounted transversely of the vehicle and the drive shaft will register with the center line thereof. The design of the engine also makes it especially useful for aircraft use where the engine could extend longitudinally along a wing of an aeroplane.

In the drawings:

Fig. 1 is a transverse cross section of the engine showing the relative location of the pistons and valves to each other and to the master cylinder.

Fig. 2 is a longitudinal cross section taken on the line 2—2 of Fig. 1, showing the master piston rods and the double ended cylinders in each block.

Fig. 3 is a partial transverse cross section taken on the line 3—3 of Fig. 2.

Fig. 4 is a fragmentary longitudinal cross section of the engine taken on the line 4—4 of Fig. 1 and showing the details of the valve actuating mechanism.

Fig. 5 illustrates a plan view of the cylinder head with the end removed as on the line 5—5 of Fig. 2.

Fig. 6 is a fragmentary cross section taken on the line 6—6 of Fig. 2 and illustrates particularly the relationship of the valves to the respective cylinders.

Figs. 7 and 8 illustrate the ring gear mechanism for actuating the valves of the engine.

The features of the invention are specifically disclosed in the following specifications in connection with a 32 cylinder combustion engine. Referring to Fig. 2, the main elements of the invention consist of aligned cylinder blocks 10, 11, 12 and 13, master power sleeves 14, located in a central bore 15, piston rods 16 and 17, a crank shaft 18, and a number of aligned pistons arranged to operate in the cylinder blocks and connected to radial arms 19 extending from a flange 10 on the midportion of the master power sleeves 14 and 15. Rods 20 extending through the radial arms 19 are connected at each end to skirtless pistons 21.

Each cylinder block consists of a circular housing having a large central bore 15 for the master power sleeves and an even number of combustion power cylinders radially spaced around the central bore. Each end of the engine is composed of two cylinder blocks placed face to face with the cylinder bores in alignment. The walls of the master cylinder 15 are provided with slots 19a which, when aligned with similar openings in an abutting block, form openings in which the radial arms 19 may reciprocate.

The spacing of the cylinders in the cylinder blocks is best shown in Fig. 1 where it will be seen that the cylinders are arranged radially from the center of the cylinder block. In order to facilitate the description of the firing order, etc., the cylinders in Fig. 1 are numbered consecutively from 22 to 29 inclusive. Each end cylinder block is provided with a head 30 having spark plug ports adapted to register with each of the cylinders in the block. The center blocks 11 and 12 are likewise provided with cylinder heads 31 having similar spark plug ports and a central opening for the piston rods 16 and 17. Spark plugs 31a are inserted in the cylinder head ports and suitable four cycle timing mechanism (not shown) is provided for the firing of the cylinders at the proper intervals. A central housing 32, which serves as a spacer and a housing for the crank shaft 18, is aligned between the heads 31. A suitable carburetor (not shown) is provided to furnish a combustible mixture to the cylinders through the intake valves 33.

The cooling of the engine can be accomplished either by the water method or the air method, though the cylinder block shown in the drawings is provided with the usual water jackets for cooling. It is considered unnecessary to enter into a detailed description of these cooling passages.

A plurality of tappet valves for the exhaust and intake of the various cylinders are provided in

the cylinder blocks, there being one intake valve and one exhaust valve for each cylinder. The intake valves are numbered 33 and the exhaust valves are numbered 34. A mechanism for actuating these tappet valves is shown especially in Figs. 3, 4, 7 and 8. It consists generally of a ring gear 35 driven by a gear 36, which is, in turn, driven from the crank shaft 18 by means of bevel gears 37 and 38 and shaft 39. The ring gear 35 is provided with risers 40 and 41 on each side which contact tappets 42 and 43 of the valves 33 and 34 (Fig. 8), said risers being spaced to actuate the valves at the proper intervals. It will be noticed that the valve stems 42 and 43 for the valves 33 and 34 are offset from each other diametrically (Fig. 6), in order that the risers 40 located nearest the center of the ring gear 35 may contact one group of valves while the risers 41 located on a slightly larger diameter on the ring gear 35 may contact the other group of valves.

The timing mechanism and valve actuating device are arranged so that the firing order of the cylinders is an even division of the number of cylinders in each block at each piston travel outward from dead center. For example, referring to Fig. 1, the even number cylinders 22, 24, 26 and 28 in block 10 are arranged to fire simultaneously and at the next return of the pistons 21, on the exhaust stroke for the even number cylinders, the odd number cylinders 23, 25, 27 and 29 will fire. There is also a direct relationship between the firing of the cylinders in the various cylinder blocks 10, 11, 12 and 13. Assuming that all of the cylinders in each block are numbered as are the cylinders in block 10 shown in Fig. 1, the even numbered cylinders in blocks 10 and 13 will fire simultaneously, and, after a complete revolution of the crank shaft, the odd numbered cylinders of cylinder blocks 10 and 13 will fire simultaneously. Likewise, the firing of cylinders in blocks 11 and 12 is simultaneous, the odd numbered cylinders of each block firing together and the even numbered cylinders in each block doing likewise. In other words, assuming that the firing of each block involves only half of the pistons at a time, the firing stroke of the even cylinders in block 10 is simultaneous with the compression stroke of the even cylinders in block 11 and with the exhaust stroke of the odd cylinders in block 11, and with the intake stroke of the odd cylinders in block 10.

It will be evident that the forces on the master power sleeves 14 due to the power cylinders will at all times be forces which are balanced in a direction parallel with the axis of the power sleeve. This permits the use of skirtless or short pistons

21 and results in a lower overall weight of the engine and a great reduction in the friction of the entire engine movement. The master sleeves 14 are provided with considerable bearing surface in the bores 15 to absorb the twisting effect 5 set up by the piston rods 16 and 17. Due to the fact that there are two piston rods acting simultaneously on the crank shaft 18 at all times, there will be perfect balance in this respect. For example, referring to Fig. 2, it will be seen that 10 the firing of the pistons in blocks 10 and 13 is simultaneous so that the counterclockwise torque applied to the crankshaft by the two piston rods 16 and 17 is exactly equal.

If desired the engine could be composed of 15 8 cylinder blocks instead of 4 as shown. In this case the additional four would be set at right angles to the present four and the additional piston rods would be attached to the same crank-shaft.

I claim:

1. In an internal combustion engine of the type having a plurality of oppositely disposed cylinder blocks each having a central longitudinal bore and a plurality of opposed double ended cylinders disposed parallel with and around said central bore, a composite piston in each of said blocks comprising a sleeve slidably fitted in said central bore, pistons facing each end of said cylinders and means connecting said sleeve and said 30 pistons rigidly together, a crankshaft, piston rod means for operatively connecting said crank-shaft and said sleeves, and intake and exhaust valves in said cylinder blocks, means for actuating said valves comprising a ring gear, driving 35 means for actuating said ring gear from the crankshaft, and risers on said ring gears for actuating said valves.

2. In an internal combustion engine of the type having a plurality of oppositely disposed cylinder blocks each having a central longitudinal bore and a plurality of opposed double ended cylinders disposed parallel with and around said central bore, a composite piston in each of said blocks comprising a sleeve slidably fitted in said 40 central bore, pistons facing each end of said cylinders and means connecting said sleeve and said pistons rigidly together, a crankshaft, piston rod means for operatively connecting said crankshaft and said sleeves, and intake and exhaust valves 45 in said cylinder blocks, means for actuating said valves comprising a ring gear, driving means for actuating said ring gear from the crankshaft, and risers on said ring gears for actuating said valves, said means being arranged to obtain symmetrical firing of said cylinders.

GEORGE GROVER, JR.
